UNITED STATES PATENT OFFICE.

ELLA NEILSON GAILLARD, OF NEW YORK, N. Y.

FOUNTAIN.

SPECIFICATION forming part of Letters Patent No. 327,673, dated October 6, 1885.

Application filed May 6, 1884. Serial No. 130,500. (No model.)

To all whom it may concern:

Be it known that I, ELLA N. GAILLARD, a citizen of the United States, residing at New York city, in the county and State of New York, have invented new and useful Improvements in Fountains, of which the following is a specification.

My invention consists of a combined portable fountain and music-box in which a spring and a flexible diaphragm are contrived with an inclosing case within the basin of a fountain for confining a quantity of water to be subjected to pressure by the spring and the diaphragm to force up a jet through a nozzle attached to the top of the dome, to provide a simple and efficient ornamental portable fountain for use in the drawing-room and elsewhere about the house when required. Said fountain also comprises means for readily re-setting the spring and refilling the forcing-case when a charge has been expelled through the nozzle, and also an arrangement of the basin for receiving and retaining the water suitably for the return of it to the forcing-case when the diaphragm is reset, and for a receptacle for cut flowers to be exhibited and at the same time to be nourished by the fountain.

My invention also consists of the spring-power musical attachment to the fountain, so contrived that the mechanism of the same will be automatically released from the holding-stop and be let free by the action of the jet-forcing spring when the fountain is in play to combine the sound of the music with the play of the fountain, and the arrangement is such that the play of the music will be automatically interrupted with intervals of rest during the run of the forcing-spring, and the arrangement is also such that the resetting of the spring-power of the music attachment is effected by the resetting of the fountain-spring, all as hereinafter fully described, reference being made to the accompanying drawings, in which—

Figure 1 is a perspective view of my improved fountain. Fig. 2 is a transverse sectional elevation, and Fig. 3 is a detail.

The letter *a* represents the exterior rim of a basin, the bottom of which is preferably raised up in a dome, *b*, to form the upper part of an inclosing-shell of a forcing case or cham-

ber, *c*, the bottom of which consists of a flexible diaphragm, *d*, of rubber or other approved material, and is provided with a strong spring, *e*, suitably arranged under the center of said diaphragm, and also seated on a supporting-plate, *f*, to exert sufficient pressure on the water in chamber *c* to force a jet up through the nozzle *g* when said spring is compressed and the chamber *c* is filled with water above it. The base *h* of the rim *a* and of the dome *b* is firmly screwed down on the margin of the diaphragm and the supporting-plate *f* to make a tight joint for preventing the escape of the water, and the center of the diaphragm is clamped between cap *i*, attached to the top of rod *j*, on the upper side of the diaphragm, and the plate *k*, also attached to said rod below the diaphragm to provide a practicable bearing for the spring against the diaphragm. The rod *j* extends down through the spring for a guiding-stay to it, and also for a means of compressing and setting the spring, for which said rod is toothed along one side to gear with a pinion, *l*, located under supporting-plate *f*, and fitted on a winding-post, *m*, that extends out through the side of the stand *n*, and has a square shank for the application of a socket-key for turning it to force down the rod and compress the spring. Near the base of the dome several valved apertures, *o*, are made in it, through which the water that falls into chamber *p* from the jet flows into the forcing-chamber *c* when the spring is forced down, the nozzle being closed by pressure of the finger on the top, or by other suitable means, so that a vacuum is produced in said pressing-chamber by depressing the diaphragm. The valves *q* are self-closing, and the pressure of the diaphragm on the water tends to keep them closed. When the spring *e* is thus compressed and the pressing-case filled, the jet will begin to flow at once on the removal of the winding-key from the post and removing the obstruction of the nozzle.

The musical attachment consists of any approved well-known form of music-box having a comb of turning forks *s*, pin-barrel *t*, and a coiled driving-spring, *u*, of any approved contrivance, as the connection of the inner end of the coil of the spring *u* to a permanently-fixed post, *v*, and the outer end of said spring connected to the crown-wheel *w*, turning loosely

on the post above the collar x , and gearing with the pinion y , connected with the end of the pin-barrel t by a ratchet-wheel, z , and a pawl, a' , which drives the barrel when turned forward by the spring, but turns backward loosely when the spring is wound up, said pinion being geared by the intermediate wheels, b' , with the pinion l on the winding-post m , so that when the key-post is turned to force the spring e down it will also wind up the spring u of the music-box.

The contrivances for periodically stopping the music apparatus and releasing it during the run of the fountain-spring consist of the stop-catch e' , which drops into a hole, e' , in the end of the pin-barrel t at each revolution of the latter, and the notched bar f' , that is made to pull out said stop-catch as often as the stud-pin g' , fitted in the lower end of the toothed bar j , passes one of the points i' of the notched bar f' , said notched bar being fitted on a pivot, j' , and ranging therefrom along up one side of toothed bar j , and having an arm, k' , and spring l' , to press the notched side forward against the stud-pin g' , and allow the stop-catch e' , to which it is connected by wire m' , to drop into the hole of the pin-barrel. The notched bar f' has a hook, n' , at the upper end that holds the rod j and the spring e at the predetermined limit of their range.

Inside of the basin a , I arrange the taper ring o' , of sheet metal, to partition the annular V-shaped space p' from the water-space p , for a receptacle in which a border of cut flowers or growing plants may be arranged around the water-space.

What I claim, and desire to secure by Letters Patent, is—

1. The combined portable spring - power

fountain and music-box, having the respective spring-power mechanism geared to one and the same key-post, substantially as described.

2. The combined portable spring - power fountain and music-box, having the respective spring-power mechanism geared to one and the same key or winding-post, the music-train having a trip-catch, and the fountain-spring having the tripper arranged therewith for releasing said trip-catch, substantially as described.

3. In a combined portable fountain and music-box, the combination of a tripper, f' , with the spring-stop e' of the music - barrel, and with the rod j , actuated by the fountain-spring when forcing the water-jet, and having pin g' , and said music-barrel having holes e' for releasing the music-barrel by the action of the fountain-spring, to furnish the music when the fountain plays, substantially as described.

4. In a combined portable fountain and music-box having spring-power mechanism for actuating the fountain, the combination of the stop-catch with the music-barrel for automatically stopping the play of the music during the run of the music driving-spring, the notched tripping - bar for releasing said catch, said notched bar being connected with the fountain-spring mechanism for periodically tripping said stop during the run of the fountain-spring, substantially as described.

In witness whereof I have hereunto signed my name in the presence of two subscribing witnesses.

ELLA NEILSON GAILLARD.
